UNITED STATES PATENT OFFICE

150,717

DESIGN FOR A VEHICLE ORNAMENT OR THE LIKE

George C. Knight, Detroit, Mich.

Application June 4, 1947, Serial No. 139,445

Term of patent 3½ years

(Cl. D14—18)

To all whom it may concern:

Be it known that I, George C. Knight, a citizen of the United States and a resident of Detroit, Wayne County, Michigan, have invented a new, original, and ornamental Design for Vehicle Ornament or the like, of which the following is a specification, reference being had to the accompanying drawing, forming part thereof.

In the drawing:

Fig. 1 is a view in side elevation of a vehicle ornament embodying the invention, showing the same applied to an automobile fender, the same being shown in dotted lines for illustrative purposes only.

Fig. 2 is an enlarged side elevation of the ornament;

Fig. 3 is a plan view of the same; and
Fig. 4 is a front elevation of the same.

I claim:

The ornamental design for a vehicle ornament or the like, as shown and described.

GEORGE C. KNIGHT.
